UNITED STATES PATENT OFFICE.

WILLIAM S. KNISELY, OF BENTON HARBOR, MICHIGAN.

CAR AND AIR-HOSE COUPLING.

1,228,569.

Specification of Letters Patent.

Patented June 5, 1917.

Original application filed January 2, 1913, Serial No. 739,582. Divided and this application filed July 10, 1915. Serial No. 39,065.

To all whom it may concern:

Be it known that I, WILLIAM S. KNISELY, a citizen of the United States of America, residing at Benton Harbor, in the county of 5 Berrien and State of Michigan, have invented a certain new and useful Improvement in Car and Air-Hose Couplings, of which the following is a specification.

This invention, relating to car couplers, is 10 a division made by the requirement of the examiner from my application Serial Number 739,582, filed January 2nd, 1913.

The object of the present invention is to provide in combination with an ordinary 15 coupler of the Janney or similar type, a coupling device for the air, water, gas or steam pipes (one or more commonly called train pipes), the same being so arranged that whenever the car couplers actually couple, 20 this train pipe coupling device positively couples and cannot be separated or broken by a slight movement of the regular couplers; but, on the other hand, can be broken when and if the cars are actually uncoupled.

25 The invention consists in a device capable of carrying out the foregoing objects, which can be easily and cheaply made and installed, which is satisfactory in operation and not readily liable to get out of order; 30 and in the specific details and features more fully set forth and claimed hereafter.

The device of this invention may be applied to any form of car coupler proper, but for convenience of illustration, it is here 35 shown applied to the specific form of coupler shown, described and claimed in my said original application.

In the drawings, which are copied from those of said original application,

40 Figure 1 is a sectional plan view of two car couplers coupled together, while

Fig. 2 shows the same parts in uncoupled position.

Fig. 3 is a vertical sectional detail view 45 through the parts in the position of Fig. 1.

Fig. 4 is a corresponding view taken on the line 4—4 of Fig. 1.

Fig. 5 is a plan view taken on the line 5—5 of Fig. 2, showing in detail the mechanism 50 of the specific invention involved in this application.

The particular form of car coupler shown in the drawings consists in general terms of a housing member 10 having in one half of 55 its face or end, which is to engage another

coupler, a recess 12, and on its other half a projecting lug 14, the lug 14 of each coupler member being adapted to enter the recess 12 in the opposite coupler member and be secured therein by a pin 16 which enters 60 through a vertical opening 18 provided for the purpose. Other numerals on the drawings below the numeral 78 refer to detail parts of this specific form of coupler included and covered by my said original application and need not be here referred to in detail.

The drawings, for convenience, show the coupling of one pair of train pipe ends 77, but obviously the mechanism may be duplicated to provide for the coupling of a plurality of such pipe ends without departing from the invention.

Each train pipe end 77 adjacent to each coupler member 10 is connected to a hollow 75 case or housing 78 suitably located on the coupler member 10, usually, as shown, on the under side thereof. These housings are not, as in the prior art, rigidly attached to the coupler body, but are so attached thereto that 80 while having a limited movement longitudinally of the coupler, a given housing can never move "inward" from the face of the coupler beyond the position which it is required to assume to insure positive coupling of the housings whenever the coupler members proper are coupled, but is, on the other hand, permitted to move "outward" 85 from the face of the coupler member 10 a limited amount so as to permit free movement of the coupler members 10 to and from each other within all the limits required, short of actual uncoupling of these members, without the housings or train pipe coupling device becoming uncoupled or detached one 90 from the other.

These results are attained in the particular case here illustrated by providing at the forward end of the housing 78 a tongue 80 adapted to slide in a suitable groove 82 in 100 the body 10 of the coupler and by providing at a suitable point, as for instance in a tail-piece 84 at the rear of the housing, a pin and slot connection between the housing and the coupler body so proportioned that the 105 housing cannot move "inward" from the given predetermined position essential for coupling with the adjacent housing when coupling takes place, but can move "outward" thereof for a substantial distance as 110

the couplers proper start to uncouple before the housings themselves are uncoupled. In the particular case here illustrated, this is accomplished by providing the tail-piece 5 84 with an elongated slot 86 through which a suitable bolt 88 entering the under side of the coupler body 10 passes, each bolt and its slot being so arranged with reference to each other that when the parts are in the position shown in Figs. 2 and 5 with the faces 10 90 of opposite housings in proximity to each other, the bolts 88 are in the forward or outer ends of their respective slots with the 15 housings bearing positively against the bolts and consequently the housings cannot move inwardly of their respective coupler bodies. On the other hand, each housing can move outward of its coupler body a distance equal to the length of its slot 86; that is to say, 20 until the inner end of that slot comes in contact with its bolt 88.

Each housing is provided with an internal valve device controlled by a plunger 92 which, on contacting with an opposite similar plunger, operates automatically in the 25 manner well known in the art, as the housings 78 are coupled to permit air or the like to pass from one train pipe 77 through the coupled housings to the other.

30 The housings themselves are detachably locked together when in coupled position by any suitable device; as for instance, a pair of springs 94, one extending from one side of each housing and detachably engaging a 35 lug or latch member 96 on the opposite housing with the result that when the two housings are thus snapped together, as shown in Fig. 5, they are held by the devices 94 with sufficient rigidity so that they do not readily 40 pull apart, but that when actual uncoupling of the car couplers takes place, each spring 94 will readily snap off from its adjacent lug or locking device 96.

45 By the construction described, the hose pipes 77 are positively and automatically coupled whenever the members 10 are coupled and owing to the fact that the housings 78 when coupled have a possible movement with reference to the car couplers proper 50 equal to the sum of the lengths of the two elongated slots 86 and that all of this movement takes place between the faces of the coupler members 10, it is obvious that there 55 can be considerable accidental separation of the coupler members 10, short of their actual uncoupling, which requires movement at least equal to the sum of the lengths of the two slots 86, without the train pipe coupling device; *i. e.*, the housings 78 and attached 60 parts, being separated or uncoupled.

Having thus described my invention, what I claim as new and desire to secure by Letters Patent, is:—

1. In combination with two car coupler members adapted to be secured together,

train pipe coupler members, one for each car coupler member and exterior thereto, mounted for free longitudinal movement with reference to its main coupler member, and means limiting the length of travel of 70 the train pipe coupler member, said means holding said train couplers rigidly in coupling position with reference to each other when the car couplers are coupling, while permitting substantial movement of the coupled train pipe couplers without beginning to uncouple them as the car couplers start to separate. 75

2. In combination with two car coupler members adapted to be secured together, 80 train pipe coupling members, one for each car coupler member and exterior thereto, mounted for free longitudinal movement with reference to its main coupler member, and a pin and slot connection between each 85 car coupler member and its train pipe coupler member so proportioned that said pins hold said train coupler members rigid in coupling position with reference to each other when the car coupler members are coupling, while permitting substantial movement of the coupled train pipe couplers without beginning to uncouple them as the car couplers start to separate. 90

3. In combination with two coupler members adapted to be secured together, train pipe coupler members, one for each car coupler member and exterior thereto, each mounted for free longitudinal movement with reference to its main coupler member, 100 means independent of the car coupling devices for detachably securing the train pipe coupler members together, and means limiting the length of travel of the train pipe coupler members, said means holding said 105 train couplers rigidly in coupling position with reference to each other when the car couplers are coupling, while permitting substantial movement of the coupled train pipe couplers without beginning to uncouple them 110 as the car couplers start to separate. 115

4. In combination with two car coupler members adapted to be secured together, train pipe coupler members, one for each car coupler member and exterior thereto, mounted for free longitudinal movement with reference to its main coupler member, 120 means independent of the car couplers detachably securing the train pipe coupler members together, and a pin and slot connection between each car coupler member and its train pipe coupler members so proportioned that said pins hold said train coupler members rigid in coupling position with reference to each other when the car coupler members are coupling, while permitting substantial movement of the coupled train pipe couplers without beginning to uncouple them as the car couplers start to separate. 125

5. In a train pipe coupling, the combina- 130

tion of a pair of supports, two train pipe 5
coupler members mounted on said supports
respectively for free sliding movement longi-
tudinally of the supports in either direction,
and means carried by each support for posi-
tively limiting the sliding movement of the
related train pipe coupler member in either
direction, said means being so positioned as
to hold the train pipe coupler members
rigidly in coupling position during the op-
eration of coupling the members, while per-
mitting movement of the coupled train pipe
couplers relatively to the supports during a
predetermined movement of said supports
away from each other.

6. In a train pipe coupling, the combina-
tion of a pair of supports, two train pipe
coupler members mounted on said supports
respectively for free sliding movement longi-
tudinally of the supports in either direc-
20

tion, and a pin and slot connection between
each train pipe coupler member and its sup-
port, positively limiting the sliding move-
ment of the related train pipe coupler mem-
ber in either direction, the pin elements of 25
said connections being so positioned as to
hold the train pipe coupler members rigidly
in coupling position during the operation of
coupling the members, while permitting
movement of the coupled train pipe couplers 30
relatively to the supports during a predeter-
mined movement of said supports away
from each other.

In witness whereof, I have hereunto sub-
scribed my name in the presence of two wit- 35
nesses.

WILLIAM S. KNISELY.
